CRIBBAGE BOARD

Filed Sept. 28, 1953

UNITED STATES PATENT OFFICE

172,268

CRIBBAGE BOARD

Ian C. L. Craig, Toronto, Ontario, Canada

Application September 28, 1953, Serial No. 26,981

Term of patent 14 years

(Cl. D34—5)

To all whom it may concern:

Be it known that I, Ian C. L. Craig, a citizen of the Dominion of Canada, resident of the city of Toronto, county of York, Province of Ontario, Canada, have invented a new, original, and ornamental Design for a Cribbage Board, of which the following is a specification, reference being had to the accompanying drawing, forming a part thereof.

The figure is a perspective view of a cribbage board, showing my new design.

I claim:

The ornamental design for a cribbage board, substantially as shown.
